(57) **CLAIM**

I claim the ornamental design for a lid to pot secure device, as shown and described.

DESCRIPTION

FIG. 1 is a perspective view of a lid to pot secure device showing my design.

FIG. 2 is a top perspective view thereof;

FIG. 3 is a top plan view thereof;

FIG. 4 is a bottom perspective view thereof;

FIG. 5 is a plan view of an assembled device thereof;

FIG. 6 is an enlarged front view of a strap assembly section taken along the line labeled FIG. 6 in FIG. 5;

FIG. 7 is an enlarged rear view of a strap assembly section taken along the line labeled FIG. 7 in FIG. 5;

FIG. 8 is a front view of a strap securing section for fastening the strap to a pot thereof;

FIG. 9 is a side view of a strap securing section for fastening the strap to a pot thereof;

FIG. 10 is a side view of the view shown in FIG. 9 showing the buckle member engageable to straps for fastening/attachment together thereof; and,

FIG. 11 is a perspective view of the secure strap device as it is fastened to a pot.

The broken line disclosure is understood to illustrate portions of a pot in which the claimed design is embodied, but which form no part of the claimed design. Other broken lines inside the design device are stitches as seen in FIGS. 1, 2, 4-6, 8 and 11.
